UNITED STATES PATENT OFFICE.

ANDREW HENDERSON, OF NEW YORK, N. Y.

DESIGN FOR A BUTTON.

44,239.

Specification for Design. Patented June 24, 1913.

Application filed December 23, 1911. Serial No. 667,550. Term of patent 14 years.

To all whom it may concern:

Be it known that I, ANDREW HENDERSON, a citizen of the United States, residing at New York city, in the county of New York and State of New York, have invented a new, original, and ornamental Design for Buttons, of which the following is a specification, reference being had to the accompanying drawing, forming part thereof.

Figure 1 is a plan view of a button showing my new design, Fig. 2 is a sectional view

through the button taken on a horizontal central line through Fig. 1, and Fig. 3 is a sectional view on a vertical central line through Fig. 1.

I claim:

The ornamental design for a button, as shown.

ANDREW HENDERSON.
